US00D667356S

(12) **United States Design Patent**
Gotschke

(10) **Patent No.:** **US D667,356 S**
(45) **Date of Patent:** **** Sep. 18, 2012**

(54) **VEHICLE WHEEL COVER**

(75) Inventor: **Wolfgang Gotschke**, Köln (DE)

(73) Assignee: **Ford Global Technologies, LLC**,
Dearborn, MI (US)

(**) Term: **14 Years**

(21) Appl. No.: **29/388,956**

(22) Filed: **Apr. 5, 2011**

(51) LOC (9) Cl. **12-16**

(52) U.S. Cl. **D12/211**

(58) Field of Classification Search **D12/204-213;**
301/37.101, 64.101, 65, 64.201

See application file for complete search history.
